UNITED STATES PATENT OFFICE.

RÜDOLF HÜNDHAÜSEN, OF HALENSEE, NEAR BERLIN, GERMANY.

TYPING-MACHINE.

No. 872,348.

Specification of Letters Patent.

Patented Dec. 3, 1907.

Application filed January 6, 1904. Serial No. 187,979.

To all whom it may concern:

Be it known that I, RÜDOLF HÜNDHAÜSEN, civil engineer, and a subject of the King of Prussia, residing at No. 27 Westfälische-5 strasse, in the town of Halensee, near Berlin, Kingdom of Prussia, and German Empire, have invented a certain new and useful Typing-Machine, of which the following is a specification.

10 The present invention relates to improvements in typographic casting machines, and particularly to the melting pots of such machines.

In the accompanying drawings,—Figure 1 15 is a vertical sectional view through a casting apparatus constructed in accordance with the present invention, said view being taken substantially on the line $x-x$ of Fig. 5; Fig. 2 is a similar view through the plunger chamber on a plane at right angles to that of Fig. 1; Figs. 3 and 4 are detail sectional views; Fig. 5 is a plan view, partly in section of the apparatus.

Referring to the drawings the pot 148, 25 which is provided with a plunger chamber 149, is heated by a suitable burner 150, the products of combustion from which are conducted away through ducts, extending up through the pot, as at k' , k^2 , k^3 , instead of 30 being caused to pass only about the outer walls thereof. An auxiliary or additional burner 151 may be employed to heat the delivery channel or nozzle 152, the products of combustion therefrom passing through 35 conduits k^4 .

Within the pot and at one side of the plunger chamber 149 therein is a chamber O 40 which is surrounded by the passages or ducts k' , and connected by suitable channels 153, 154, with the main chamber of the pot and with said plunger chamber.

The arrangement of the chamber O with 45 relation to the ducts or passages for the products of combustion from the burner 150 is such that the metal in said chamber is subjected to the highest temperature; and when the plunger is depressed a circulation of the molten metal from the well, through the ducts 153, 154, the chamber O , and 50 ducts in the nozzle is created, whereby all of the parts are kept properly heated. The ducts 201 and 202 as shown in Figs. 3 and 4, communicate with the atmosphere and with a chamber in the end piece 200 of the nozzle. 55 To reduce the amount of radiation of heat

the pot is preferably provided with a jacket 203 having a lining 204 of non-heat conducting material.

To enable the pot to be completely emptied an opening is formed at the lowest point 60 in the casting channel, which opening is closed by a removable screw plug 203^a. The space between the upper end of the plug 203^a and the upper wall of the channel forms a circulation opening or passage similar to 154.

The casting pot is moved to and from the mold by means generally similar to those heretofore employed in machines of the same character. These means are clearly shown 70 in Fig. 1 where 205 designates a pivotally mounted plate connected with the pot, and having a curved face against which acts a cam disk 218. Said plate 205 bears on a roller 210 arranged at the lower end of an 75 arm 208, pivotally connected with the pot at 209 and having its upper end connected by a spring 206 with an arm 207 on the frame of the machine. The spring 206 is connected with the arm 207 by an adjusting screw 211, 80 by means of which the tension of the spring may be easily varied as desired. By this construction it will be seen that the spring 206 is arranged at some distance from the pot and is therefore not exposed to high heat. 85

The rod 212 of the plunger is connected to a lever 213 which is in turn connected, by a spring 214, to a lever 215, adapted to be rocked by the cam 218 engaging a roller 217 carried by a link 216 that is connected with 90 said lever 215. The lever 213 is positively lifted by a disk 215^a which bears against a depending lug 213^b on said lever. A gap or notch 215^b is formed in the periphery of the disk 215^a, and when the lug 213^b is in alignment with the gap and the cam 218 passes from engagement with the roller 217, the spring 214 will move the plunger suddenly 95 downward.

It will be seen that by connecting the lower 100 end of the spring to a movable member it is possible to increase the tension on the spring 214 just preceding the release of the plunger so that the maximum force will be exerted on the downward movement of the plunger. 105 That is, the cam 218 is of such form and so positioned relative to the gap 215^b that it will force the lever 215 to its lowest position as the gap 215^b approaches the lug 213^a; and therefore when the said gap is beneath 110

the lug and the roller 217 is released the spring 214 will be exerting its maximum pull.

The operation of the machine herein described may be briefly stated as follows: When an assembled line of matrices has reached the casting position, the melting pot is advanced by its cam and by means of the spring 206 yieldingly pressed against the form 106. The plunger is then released by the cam 215 and descending under the action of the spring 214 ejects molten metal through the delivery channel 152 and end piece 200 into the form. A portion of the metal 15 turns to the melting pot through the ducts 154, 201, 202, but these ducts are so small that sufficient metal is ejected into the form to completely fill it and the matrices. After a line has been cast the plunger is rapidly 20 raised by the cam 215 and a fresh supply of molten metal falls from the chamber O, containing the hottest portion of the metal, into the well of the pump, through the holes 153. After the plunger has been raised the cam 25 218 acting on the lever 215 again increases the tension of the spring to its maximum strength, such tension having been diminished after the descent of the plunger. By arranging the parts so that the tension of the 30 spring is materially reduced before the plunger is raised and gradually increased prior to the next downward movement of the plunger, it is possible to use a strong spring

and shorten the time required for lifting the plunger. The strong tension of the spring 35 causes the plunger to descend suddenly so that the form is rapidly and completely filled with metal notwithstanding that some escapes from the ducts 154, 201, 202 and 153.

Having thus described the invention what 40 is claimed and desired to be secured by Letters Patent is,—

1. In a typographic casting machine, a melting pot having its interior divided into a main receptacle, a plunger chamber and a 45 primary heating chamber which extends parallel to the plunger chamber and communicates with both the main receptacle and plunger chamber through horizontal ducts, whereby when a plunger is depressed in the 50 plunger chamber a circulation of heated metal is created from said primary heating chamber.

2. In a typographic casting machine, the combination with a melting pot and a plunger working in said pot, of a lever for actuating said plunger, a second lever, a cam adapted to vibrate said second lever, and a 55 spring connecting said levers.

In witness whereof, I have hereunto signed 60 my name in the presence of two subscribing witnesses.

RÜDOLF HÜNDHAÜSEN.
